UNITED STATES PATENT OFFICE.

GEORGE M. MOWL, OF MONESSEN, PENNSYLVANIA, ASSIGNOR TO AMERICAN SHEET AND TIN PLATE COMPANY, OF PITTSBURGH, PENNSYLVANIA, A CORPORATION OF NEW JERSEY.

PACK-OPENING MACHINE.

Application filed January 15, 1926. Serial No. 81,463.

This invention relates to machines for opening packs of sheets or plates, and has for its object the provision of an improved machine of this class which will quickly 5 open or separate packs of sheets or plates which have become stuck together in the rolling operation.

Another object is to provide a machine of this class in which all the rolls engaging the 10 sheets or plates will have the same surface speed and, therefore, slippage of the rolls on the plates is entirely eliminated.

A further object is to provide a novel 15 form of drive mechanism for the separating rolls whereby said rolls may be operated in either forward or reverse directions without changing the direction of rotation of the motor.

The machine of this invention is primarily 20 adapted for opening packs of "stickers" in making sheet and tin plates. In rolling tin bar into tin plates two short pieces of tin bar are placed one on top of the other and are rolled to a predetermined width, length 25 and gage. The resultant product from the above operation is known as a "pair" and is next doubled upon itself so as to have four thicknesses of metal and is again rolled, the resultant product being known as a "pack". 30 The so formed pack is then sheared along its edges to make four sheared sheets, and the pack is then separated into individual sheets.

Frequently the sheets stick together. In 35 such case a workman will separate the one corner and by placing his foot on some of the plates and pulling on the upper one with a pair of tongs will separate the top sheet from the balance. Sometimes, however, the plates stick so tightly together that the work- 40 man can not pull them apart and it has been the practice heretofore to lay such packs, known as "stickers", aside so as to not interrupt the usual operation of the mill, and such stickers were then separated by other 45 workmen with special tools. The separation of stickers required considerable labor and expense and often resulted in the spoiling of numerous sheets.

The present machine provides means for 50 readily separating "stickers" with a minimum of labor and at such small expense that the cost of the machine is saved in about one month's time.

In the drawings:

Figure 1 is a plan of a machine embody- 55 ing this invention.

Figure 2 is a side elevation thereof.

Figure 3 is a transverse sectional elevation on the line III—III of Figure 2.

Figure 4 is a detail sectional view through 60 the control clutch.

Referring more particularly to the drawings, the numeral 2 designates the base or bed plate of the machine which may be permanently mounted on a suitable foundation 65 or, if desired, may be mounted on a truck so that the machine may be moved from place to place in the mill.

A pair of housing stands 3 and 4 having windows 5 are secured to the bed plate 2. 70 Roll bearing blocks 7 are slidably mounted in the windows 5 of the stands 3 and 4 and have two pairs of rolls 8 and 9, and 10 and 11 journaled therein. The rolls 8, 9, 10 and 11 are all of the same diameter and are arranged in vertical alinement.

The stands 3 and 4 are connected together at their upper ends by a separator 12 which serves to form a rigid structure.

The top bearing blocks 7 in which the 80 uppermost roll 8 is journaled are provided with an aperture 13^a to receive the reduced lower end 13^b of an adjusting screw 13. The adjusting screws 13 extend freely through suitable apertures in the separator 12 and 85 have a threaded portion of shank 14 on which is mounted a nut 15. The nuts 15 fit snugly in and are held against rotation by the windows 5. A coil spring 16 is mounted on the shank of each of the screws 13 between the 90 nuts 15 and the separator 12 which closes the top of the windows 5. A hand-wheel 17 is mounted on the upper end of the screws 13. By turning the hand-wheels 17 the screws 13 are rotated to move the nut along the 95 threaded portion 14 of the shank, thereby increasing or decreasing the tension of the springs 16 which tension will force the screws against the uppermost bearing block 7 and thereby change the pressure of the rolls 100 8, 9, 10 and 11.

The rolls 8, 9, 10 and 11 all have their reduced bearing portions or necks extended at one end so as to project outwardly beyond the stand 4 and provide stub portions 19, 20, 105 21 and 22 to receive the pinion gears 23, 24,

25 and 26, all of which are of the same size and are meshed so as to positively drive all of the rolls at the same speed.

The lowermost roll 11 has its neck at the 5 end opposite the extension 22 extended to form a stub portion 27 to receive a power pinion 28.

The power for operating the machine is furnished by a motor 29 mounted on the base 10 or bed plate 2 and having its armature shaft coupled to a power shaft 30 journaled in bearings 31. The shaft 30 has a sprocket 32 fixedly mounted thereon which is connected by a chain 33 to a sprocket 34 loosely mounted 15 for free rotation on a drive shaft 35.

The shaft 35 is journaled in bearings 36 and is coupled at 37 to a standard speed reducing gearing element 38 (not shown in detail) which has a pinion 39 in mesh with 20 the drive or power pinion 28 on the roll 11.

The shaft 30 also has a pinion 40 fixedly mounted thereon which is in mesh with a gear 41 loosely mounted for free rotation on the shaft 35.

25 The sprocket 34 and gear 41 are provided with clutch rims 42 and 43, respectively, adapted to receive and be engaged by a double-faced clutch member 44 slidably mounted on the shaft 35 so as to be moved 30 into engagement with either of the clutch rims 42 or 43, and held against rotation on the shaft by a suitable key 45.

The sprockets 32 and 34 being connected directly by the chain 33 will rotate in the 35 same direction as the shaft 30, while the gears 40 and 41 being meshed will cause the gear 41 to rotate in the opposite direction to the shaft 30 and pinion gear 40. Therefore, when the clutch member 44 is in engagement 40 with the clutch rim 43 on the gear 41 the rolls will be operated in the opposite direction than when the clutch is engaged with the rim 42 on the sprocket 34.

A suitable clutch operating lever 46 is 45 provided for manually controlling the position of the clutch member 44.

An inclined entrance guide plate 47 is mounted between the stands 3 and 4 on the entrance side of the machine and is supported 50 on an angle bar 48. The lower or forward end of the plate 47 is slightly short of the bite of the lower pair of rolls 10 and 11 so as to guide the sheets therebetween.

A combined guard and separator plate 49 55 bent in a curved substantially semi-circular shape is mounted between the stands 3 and 4 in front of the upper roll 10 of the lower pair of rolls and the lower roll 9 of the upper pair of rolls and serves to separate or 60 divide the plate being separated from the pack and also to prevent the operator accidentally getting his hand caught between the rolls 9 and 10.

A second guard plate 50 is welded or otherwise secured to the bar or rod 51 secured

between the stands 3 and 4 on the entrance side of the machine in front of the top roll 8 and prevents the operator from getting his hand caught between the rolls 8 and 9.

A pair of guide plates 52 and 53 are secured 70 between the stands 3 and 4 on the exit side of the machine and are arranged to receive the sheet separated from the pack as the sheet passes from the bite of the rolls 8 and 9.

A receiving plate or platform 54 is mounted 75 between the stands 3 and 4 on the exit side of the machine below the bite of the rolls 10 and 11 to receive the pack of sheets as they pass from between said rolls.

In operation the operator takes a pack of 80 stuck sheets, known as a sticker, and opens one corner by pulling on the top sheet with a pair of tongs, after the corner of the top sheet is separated for a short distance, the pack is fed along the entrance guide plate 47 and the corner of the top sheet entered 85 into the bite of the top pair of rolls 8 and 9, while the remainder of the pack enters the bite of the lower pair of rolls 10 and 11. 90 The rolls then pull the sheet and pack through the machine, tearing the top sheet loose. The pack may be re-entered as many times as necessary to separate all the sheets.

By providing separating rolls all of the 95 same diameter and driven at the same speed, the surface speed of all the rolls is the same. Therefore, there is no slippage of any of the rolls on the sheets and consequently the 100 sheets are not scratched or scored as would be the case were the rolls of different diameter or operated at different speeds.

The novel drive arrangement of this machine, whereby the direction of rotation of the rolls may be immediately reversed by 105 simply throwing the clutch lever 46, is particularly valuable in a machine of this class, since if a cobble should be made the sheets may be ruined or the machine broken unless the machine is immediately reversed.

110 While I have shown and described one specific embodiment of my invention it will be understood that I do not wish to be limited thereto since various modifications may be made without departing from the scope 115 of my invention as defined in the appended claims.

I claim:

1. In a machine for opening sheets, the 120 combination of a pair of roll stands, two pairs of rolls journaled on said stands, all of said rolls being of the same diameter and arranged in vertical alinement, a combined guard and separator plate curved to a substantially semi-circular shape mounted between 125 and supported on said stands, said plate extending in front of said rolls from a point above the longitudinal axis of the lower one of the upper pair of rolls and to a point below the longitudinal axis of the up- 130

per one of the lower pair of rolls, and means for positively driving all of said rolls in either direction at the same surface speed, said means including gearing connecting all 5 of said rolls together, a source of power, a power shaft connected to said source of power, a drive shaft geared to one of said rolls, forward and reverse drive connections between said power shaft and said drive shaft, 10 and a clutch member on said drive shaft adapted to connect either said forward or reverse drive connections with said drive shaft to cause the rotation of said shaft and rolls in a forward or reverse direction.

15 2. In a machine for opening sheets, the combination of a pair of roll stands, two pairs of rolls journaled in said stands, all of said rolls being of the same diameter and arranged in vertical alinement, a combined 20 guard and separator plate curved to a substantially semi-circular shape mounted be-

tween and supported on said stands, said plate extending in front of said rolls from a point above the longitudinal axis of the lower one of the upper pair of rolls and to a 25 point below the longitudinal axis of the upper one of the lower pair of rolls, and means for positively driving all of said rolls in either direction at the same surface speed, said means including a source of power, gearing connecting all of said rolls together, and means connecting said source of power to said gearing, said last named means including a double acting clutch mechanism adapted to be engaged to selected elements rotating in opposite directions to thereby cause the rotation of said rolls in a forward and reverse direction. 30 35

In testimony whereof I have hereunto signed my name.

GEORGE M. MOWL.
